SUCTION CLEANER

Paul E. Frantz, Euclid, Ohio, assignor to The Apex Electrical Manufacturing Company, Cleveland, Ohio, a corporation of Ohio

Application July 5, 1940, Serial No. 343,921

3 Claims. (Cl. 285—167)

This invention relates to suction cleaners and more particularly to the tank or cylinder type of suction cleaner, wherein a portable suction-producing unit is provided with a flexible hose adapted to be connected to dusting and cleaning tools.

It is among the objects of my invention to provide a suction cleaner of the type referred to, in which the suction-producing unit and the dust-collecting receptacle are enclosed within an oblong tank or shell which may be easily moved about over a supporting surface.

It is a further object of my invention to provide a suction cleaner according to the preceding object, wherein a carrying handle for the cleaner is constructed and arranged so as to comprise a control for the switch for the motor in the suction-producing unit.

It is a further object of my invention to provide a suction cleaner of the type referred to wherein the flexible hose leading from the cleaner to the dusting tools is fitted with a coupling which will effectively seal the joint between the hose and the cleaner and which will facilitate the attachment and detachment of the hose.

It is a further object of my invention to provide a cleaner of the character described, wherein a replaceable filter is arranged in the air stream between the dust-collecting bag and the suction-producing unit.

It is also an object of my invention to provide a suction cleaner according to the preceding objects wherein the tank or shell is supported by runners having a simple and efficient means for attaching the runners to the cleaner body.

Further objects and advantages relating to simplicity in construction and efficiency in use will appear from the following description and appended drawings, wherein:

Figure 1 is an elevation partly in section of a section cleaner made according to my invention;

Figure 2 is an elevation partly in section showing the attachment of the flexible hose to the suction cleaner by means of a coupling made according to my invention;

Figure 3 is a plan view of the suction cleaner with parts broken away;

Figure 4 is a plan view with parts in section of the flexible hose and coupling device forming a part of my suction cleaner;

Figure 5 is a front elevation showing the runner mounting employed in my suction cleaner;

Figure 6 is an elevation with parts in section showing the runner mounting;

Figure 7 is an enlarged sectional view show-

ing the handle and switch mounting made according to my invention;

Figure 8 is a sectional view taken along the lines 8—8 of Figure 7; and

Figure 9 is a sectional view of a modified form of handle and switch assembly.

Referring to the drawings, the suction cleaner which I have provided comprises a casing which in the preferred form consists of a cylindrical shell 6 having end bells or caps 7 and 8. A suction-producing unit is indicated in its entirety at 9, comprising a motor 10 and a fan chamber 11, said unit being mounted at the rear end of the casing 6, adjacent the end bell 8. The unit 9 is designed to draw air through the inlet opening 12, thence through the pores of the fabric dust bag 13, thence through the germ trap or filter 14, around the motor 10 and exhaust the air through the outlet opening 15.

To dampen the noise occasioned by the motor and fan unit, and to facilitate the assembly, the unit 9 is preferably supported within the casing 6 by the annular rubber rings 17 and 18. The rubber ring 17 is shaped in cross-section as shown in Figure 1 so that the forward face thereof bears against a shoulder on the metal ring 19 which is spot-welded or otherwise secured to the casing 6. The rubber ring 18 bears against a metal ring 21 carried within an annular recess in the open end of the end bell 8 so that upon assembly of the end bell 8 with the casing 6, the metal ring 21 is drawn against the rubber ring 18 which in turn urges the entire fan and motor unit 9 axially to effect a snug engagement of the forward rubber ring 17 with the ring 19.

Longitudinally extending tie rods 22 are carried by the end bell 8 and the threaded nuts 23 may be drawn up so as to clamp securely the unit 9 in position through the medium of the end bell 8. The rods 22 are preferably provided with tubes or sleeves of insulating material 22a in that portion of their length adjacent the fan and motor unit 9. This it will be observed that I have provided a construction wherein the entire motor and fan unit and the end bell 8 are effectively secured in their assembled position by longitudinally extending tie rods 22. The motor and fan unit are insulated both electrically and with respect to noise in the unit by the rubber ring mounting 17—18 so that the unit is safe and quiet in operation. The fan is preferably of the multi-stage or progressive type, although the specific construction employed in fan and motor does not form an essential part of my invention.

The forward end bell 7 is detachably secured

to the casing 6 by means of the toggle clamps 25 and between the abutting edges of the casing 6 and the end bell 7 is carried the annular rubber ring 26 which not only seals the joint between the end bell 7 and the casing 6, but also carries a metal ring 27 to which is secured the open end of the fabric dust bag 13.

By means of the dust bag mounting which I have provided, the releasing of the clamps 25 facilitates the removal of the dust bag 13 through the forward open end of the casing 6 for the purpose of emptying the bag.

Tests have shown that the exhaust from some of the cleaners of the cylinder type carry fine particles of dust and germs which have been drawn through the pores of the dust bag. To eliminate the danger to health associated with exhaust air of this character I have inserted in the air stream between the dust bag and the unit 9, a germ trap or filter 14 which comprises a felted or fibrous pad which may be impregnated with antiseptic solutions. The filter unit 14 may be easily removed through the open front end of the casing 6 after the dust bag is removed, and the filter when in operating position is retained by having a snug frictional fit within the annular recess formed in the metal ring 19. Preferably the filter unit comprises a ring 29 of rigid material having a channel cross section, a pair of spaced metal screen members 30 to retain the pad 31 in position and a handle 32 integrally formed with the ring 29.

According to my invention the casing 6 is supported on the floor and spaced therefrom by a runner assembly comprising spaced runners 40 and 41 secured to longitudinally-spaced saddle brackets 42 and 43. The saddle brackets are secured to the casing as shown in Figure 5 by screws or the like 44 and the enlarged end portions of the saddle brackets are bored axially to receive the inturned ends of the runners.

Preferably the inturned ends of the runners are secured to the brackets and retained therein against rotation with respect to the bracket by means of the screw and pin connection best shown in Figure 6. The inturned ends of the runners are axially bored and threaded to receive the screws 45 and 46, respectively. Removable pins 47 and 48 extend transversely of the end of the runner. To remove the runner 40 from the bracket as shown in Figure 6, the screw 46 is removed and the runner section 42a is pulled rearwardly by springing said section sufficiently to expose the transverse pin 48, which normally sets in a socket in the rear face of the bracket 43. The pin 48 may then be removed. Thereafter the screw 45 at the forward end of the runner may be removed and by sliding the entire runner forwardly, the inturned front end of the runner may be moved axially so as to free the same from the bracket 42. Thereafter the entire runner assembly may be slid rearwardly with respect to the bracket 43 so as to free the inturned rearward end of the runner.

When the runners are in their supporting position as shown in Figure 6, the transverse pins 47 and 48 insure that there will be no rotating movement of the runner with respect to the brackets 42-43. The runner mounting means I have provided thus renders the runner removable for purposes of repair and assembly.

The carrying handle and switch arrangement which I have provided comprises a longitudinally extending, rigid handle 50 which is preferably of metal or molded plastic and is pivoted as at

51 on its forward end and is mounted for movement within the bracket 52 at its rearward end. Enclosed within the bracket 52 is the motor switch 53 having push button operating means 54 bearing against an integrally-formed lug 55 on the carrying handle. The carrying handle is normally urged upwardly within the bracket 52 by means of the coil spring 56 which surrounds a bolt 54a anchored in the top wall of the end bell 8.

The upper end of the coil spring 56 bears against a washer 57 which in turn bears against the under side of the lower face of the end of the handle 50 and thus the said end of the handle 50 is normally urged upwardly to the limits defined by the length of the bolt 54a. To restrain the handle from upward movement beyond the side walls of the bracket 52, the end of the handle adjacent the switch portion 54 is provided with a pair of spaced, depending apertured portions 59.

The lower end of the spring 56 bears against a U-shaped clip 58 having outwardly turned ends 60 which extend through the apertures 25 in the members 59. The apertures in the member 59 permit the handle to be moved downwardly against the action of the spring 56 so that the boss 55 on the handle will actuate the push button 54 on the switch 53. Upon release 30 of the handle, the spring 56 will restore the handle to its position shown in Figures 7 and 8, whereby the handle may serve its carrying function with respect to the suction cleaner.

The switch 53 is of the conventional push-button type, wherein successive depressing movements of the button 54 establish or interrupt the electrical circuit through the switch.

My cleaner is provided with a flexible extension hose 65 (see Fig. 4) having a coupling 66 at one end thereof adapted to be secured to the casing 6 and a nozzle-receiving portion 67 at the other end which is adapted to have applied thereto various forms of dusting tools or cleaning brushes. In cleaners of the type referred to, the flexible hose in addition to serving as a conduit for the device is often employed to pull the entire suction cleaner about the floor. To accomplish this double function, it is important that the coupling connection between the hose 55 and the cleaner not only seal the joint between the hose and the cleaner, but that a connection maintained be strong enough to sustain the pull occasioned by pulling the cleaner about the floor.

It is also advantageous that the coupling include a swivel joint between the hose and the cleaner so that the frequent turning movements occasioned by manipulation of the dusting tools will not twist or kink the flexible hose.

To achieve the functions above outlined, I have provided a coupling indicated in its entirety at 66, which comprises a tubular element 67 which is cemented or otherwise secured to the flexible hose as at 68 at one end and which is rolled outwardly as at 69 at its other end to overhang a portion of the coupling member 70. A bead 71 is rolled intermediate the length of the tube 67 to provide a restraining shoulder for ring 72 which abuts the inner end of the coupling member 70. The ring 72 and the outwardly turned portion 69 of the tube have a free-turning fit with the coupling member 70 so as to provide the swivel joint connection between the flexible tube 65 and the suction cleaner casing. The coupling member 70 is in threaded engagement

with the outer coupling member 72a. A portion 13 of the coupling member 72a telescopically fits over the outer wall of the coupling member 70 and between said portion 13 and the end portion 14 of the member 70 is arranged an annular rubber ring 75. Washers 76 and 77 are arranged on each side of the rubber ring 75. A coil spring 78 is also arranged in the annular space between the portion 13 and 14 with the inner periphery of the coil spring 78 bearing against an inclined shoulder 79 so that movement of the coil spring toward the open end of the coupling will cause the coil spring to increase in diameter.

As shown in Figure 2, the coil spring 78 has been urged axially up the incline 79 by turning the member 72a so that a portion of the coil spring is moved outwardly into a groove 80 formed in the opening of the end bell. As soon as the coiled spring has moved into a groove 80, as shown in Figure 2, further axial movement of the rubber ring 75 is restrained and the continued turning of the outer coupling member 72 causes the rubber ring to increase its diameter and seal the joint between the coupling member 70 and the annular wall of the opening in the end bell.

To insure that there will be relative rotational movement between the inner and outer coupling members 70 and 72, I have provided the inner coupling member 70 with axially extending pins 82 which are adapted to engage lugs 83 on the radial wall 84 at the inner end of the end bell opening.

The outer coupling member 72a is suitably grooved or knurled as shown at 85, so that the user of the cleaner may with one simple movement insert the coupling 66 within the opening in the end bell 7 and by a slight turning motion expand the coil spring 78 into its locking position and also expand the rubber ring 75 into sealing position.

From the foregoing description of the flexible hose and coupling therefor, it will be understood that I have provided a coupling wherein an expansible locking means and an expansible sealing ring are jointly acted upon and cooperate with each other to effect the functions for which they are designed by a simple, turning movement of one portion of the coupling.

A suction cleaner made according to my invention is also suited for use with paint-spraying and demothing devices which utilize the exhaust or blowing force of the cleaner rather than the suction. To adapt my cleaner to such uses, I have provided the rear end bell exhaust opening 15 with an annular wall 90 having a groove 91, which wall and groove are adapted to receive the hose coupling 66 in the manner heretofore described in connection with the inlet or suction end of the cleaner. The nozzle portion 67 of the flexible hose may then be fitted with demothing or paint-spraying devices which are operated by the pressure developed by the motor and fan unit 9.

In the use of the last-named devices, the dust bag and filter may be removed from the cleaner so as to reduce the resistance to air flow through this portion of the cleaner and effect a consequent raising of the pressure by the unit 9.

In Figure 9 I have shown a modified form of my suction cleaner, wherein the casing 100 is tapered from the forward end toward the rear end bell 101. The fan and motor unit 102 is mounted within the casing 100 substantially in the same manner as in the embodiment of my

invention first described. In the form of my invention illustrated in Figure 9, the carrying handle 103 comprises a molded rubber section which is anchored as at 104 to the cleaner casing on its forward end. The rear end of the handle is proportioned to overhang a section of the end bell above the motor switch 105. The extreme end of the handle as at 106 is arranged within a metal handle bracket 107. The rear end of the handle 103 is secured to the end bell 101 through the medium of the transverse pin 112. The pin 112 is mounted to have a limited axial movement in slot 112a formed in the side walls of the handle bracket 107. The bracket 107 is secured to the end bell by means of cap screws or the like 108. An integrally-formed, contact portion 109 of the handle is arranged to bear against push button 110 of the switch and the flexibility inherent in the rubber of the handle permits the end portion thereof to be flexed so as to effect actuation of the push button 110.

To insure that the portion 109 will be restored to its raised position, as shown in Figure 9, a leaf spring 111 is arranged between the handle portion 109 and the end bell 101. The leaf spring is preferably held in assembled position by a loop surrounding the transverse pin 112. The pin and slot arrangement 112-112a permits a sliding and flexing of the handle which facilitates the switch actuation described and the movement of the handle to convenient carrying position.

The operation of the handle and switch construction shown in the modification of Figure 9 is substantially like that in the embodiment first described, except that in the modified form, the entire handle does not have a bodily movement throughout and it is only the handle portion 109 which partakes of any appreciable movement in actuating the switch. In both forms of my invention, however, the switch button is housed by the handle and handle bracket and is actuated by the movement of at least a portion of the carrying handle.

Although I have described my invention and modifications thereof, in considerable detail, it will be appreciated by those skilled in the art that further modifications and changes may be made therein, without departing from the scope of the invention as defined in the following claims.

Having thus described my invention, what I claim is:

1. A suction cleaner having an inlet opening provided with a smooth, cylindrical portion having an annular groove, a hose, a coupling on the end of said hose provided with an expansible member adapted to be expanded within the said smooth, cylindrical portion of the inlet opening to form a seal therewith, an expansible member in engagement with said first-named expansible member adapted to be outwardly expanded into said groove to restrain the coupling against longitudinal movement with respect to the cleaner and means movable longitudinally of the coupling to expand both of said members.

2. A suction cleaner having an inlet opening provided with a smooth cylindrical portion having an annular groove, a hose, a coupling on the end of said hose provided with an outwardly expansible resilient sleeve adapted to be expanded within the said smooth cylindrical portion of the inlet opening to form a seal therewith, an expansible annular metallic member coaxially arranged in contact with said sleeve and adapted to be

outwardly expanded into said groove to restrain the coupling against longitudinal movement with respect to the cleaner and means movable longitudinally of the coupling to expand said sleeve and member.

3. In combination a fitting having a smooth cylindrical bore provided with an annular groove, a hose, a coupling on the end of said hose adapted to fit within said bore, a flange on the end of said coupling, means on said flange and on said fitting to prevent relative rotation between the fitting and the flange, a cam portion on said

flange, an annular outwardly expansible ring abutting said cam portion, an outwardly expansible sleeve coaxially arranged on the coupling adjacent said ring, means on said coupling in engagement with said sleeve to move the sleeve and ring longitudinally of the coupling whereby the cam portion effects outward expansion of said ring into said groove and the sleeve is outwardly expanded into sealing engagement with the fitting.

PAUL E. FRANTZ.
